[57] ABSTRACT

[21] Appl. No.: 421,028

A grinding machine with a stepping motor for feed
movements, with a slow pulse generator and a fast
pulse generator, and with a control means for intro-
ducing pulse from the fast generator during one part
of the grinding cycle and from the slow generator dur-
ing another portion of the grinding cycle.

GRINDING MACHINE

BACKGROUND OF THE INVENTION

It has become common practice to use a stepping motor for regulating the transverse movements in a grinding machine. A typical grinding machine of this type is shown in the patent of Robillard U.S. Pat. No. 3,634,979 which issued on Jan. 18, 1972. The stepping rates on feed systems used on such grinders are around 350 steps per second. This rate, when used on a 3-digit feed system at 0.00050 inch of diameter per step, can be used during the grinding portion of the cycle adequately. However, when the full three digits are used as (during a retraction, dressing, and return cycle portion of the cycle), it may take 5.7 seconds to complete the resetting of the wheel. This amount of time, although undesirable, has been accepted in the past on machines in which the workpieces are loaded by hand. When such systems are used on high production machines where the workpieces are automatically loaded and unloaded from the machine, this reset time becomes completely unacceptable. This is even more so when the machine is of the "controlled force" type in which the grinding cycle time has been reduced to a very small amount. In other words, in such machines the amount of the cycle from the time of loading the workpiece to the time of unloading it, is occupied for a very little portion of the cycle time in the actual grinding. The rest of the cycle is devoted to moving the wheel out for a dress and then returning it to finish the grinding portion of the cycle. Attempts in the past to overcome this difficulty have been less than successful, because of the inertial loads involved in starting and stopping a wheelhead moving at high speed and also because of the difficulty in keeping the stepping motor "in step" with the train of pulses. These and other difficulties experienced with the prior art devices have been obviated in a novel manner by the present invention.

It is, therefore, an outstanding object of the invention to provide a grinding machine using a stepping motor feed in which relatively long distance travel portions of the grinding cycle are traversed at a high rate of speed.

Another object of this invention is the provision of a stepping motor feed grinding machine in which a low and a high speed pulsing rate is used without difficulties experienced due to shock in changing from one to another.

A further object of the present invention is the provision of a grinding machine having a stepping motor for feed in which changes from low-speed pulsing to high-speed pulsing take place without the stepping motor getting out of step.

It is another object of the instant invention to provide a grinding machine having an interrupt-to-dress cycle in which the portion of the cycle devoted to retraction for dress and to return, is reduced to an acceptable value.

A further object of the invention is the provision of a grinding machine using a pulsing motor feed, in which any interruption of the grinding cycle does not result in loss of synchronization.

With these and other objects in view, as will be apparent to those skilled in the art, the invention resides in the combination of parts set forth in the specification and covered by the claims appended hereto.

SUMMARY OF THE INVENTION

In general, the invention consists of a grinding machine having a base, having a workhead slide mounted on the base, having a wheelhead slide mounted on the base, and having a feed mechanism including a stepping motor for producing transverse relative movement between the slides to bring about a grinding cycle. A low-speed pulse generator is provided for producing pulses at a first rate and a high-speed generator is provided for producing pulses at a second rate which is substantially greater than the first rate. A control means is provided for introducing pulses from the low-speed generator to the stepping motor during a portion of the grinding cycle and for introducing pulses from the high-speed generator to the stepping motor during another portion of the grinding cycle.

More specifically, means is provided for smoothly shifting from one pulse rate to the other without loss of stepping motor synchronization. This means for shifting provides for changing the rate along a selected acceleration curve from the smaller to the larger of the two pulse rates and along a selected deceleration curve from the larger to the smaller.

The control means connects the first pulse generator to the stepping motor to retract the wheel from the workpiece to a base line for treatment by the dressing apparatus and returns it to the workpiece for further grinding. A buffer counter is loaded with a predetermined pulse count to determine the point at which deceleration begins during retraction and again during return. The control means acts to feed the second pulse rate to a down-counter and to the deceleration counter before feeding the second pulse rate to the stepping motor for the retraction movement.

BRIEF DESCRIPTION OF THE DRAWINGS

The character of the invention, however, may be best understood by reference to one of its structural forms, as illustrated by the accompanying drawings, in which:

FIG. 1 is a perspective view of a grinding machine embodying the principles of the present invention,

FIG. 2 is an enlarged perspective view of the grinding machine with the covers removed,

FIG. 3 is a sectional view of a portion of the grinding machine taken on the line III—III of FIG. 4,

FIG. 4 is a plan view of a portion of the grinding machine with parts broken away,

FIGS. 5-19 are electrical schematic diagrams of a control means forming part of the grinding machine, and

FIG. 20 is a diagram showing the manner in which the electrical diagrams of FIGS. 5-19 fit together to make up a complete circuit.

DESCRIPTION OF THE PREFERRED EMBODIMENT

Referring first to FIG. 1, wherein are best shown the general features of the invention, the grinding machine, indicated generally by the reference numeral 10, is shown as having a base 11 at the upper portion of which is provided with an apron 12. A cover 13 is mounted on the top of the apron and is provided with a window 14 through which the operator can observe the grinding operation. A wheelhead motor 15 is exposed on the top of the base and a control cabinet 16 extends upwardly from the rear of the base. This grind-

ing machine is of the type intended for internal grinding and a feed chute 17 extends upwardly through the cover 13 for introducing into the machine a plurality of small workpieces, such as roller bearing races. In the preferred embodiment this machine is the so-called "miniature internal grinding machine" which is used for small ball bearing races and like workpieces in situations where the grinding cycle is very small and yet the desired accuracy of finishing is very high, so that it is reasonable to use an interrupt-to-dress cycle to produce a fine finish on the workpieces.

Referring now to FIG. 2, which shows the apron 12 and the cover 13 removed, it can be seen that the base has mounted on its upper surface a workhead table 18 and a wheelhead table 19. The workhead table is suitably mounted to carry a workhead 21 for movement transversely of the machine (from front to back). The wheelhead table 19 is adapted to slide longitudinally of the machine (from right to left) and it, of course, carries the wheelhead motor 15 described above. Also mounted on the wheelhead table 19 and suitably connected to the wheelhead motor 15 is a wheelhead 22 from which extends a rotatably mounted spindle 23 whose outer end carries an abrasive wheel 24. Suitable dogs 25 are mounted on the front of the wheelhead table 19 and engage switches 26 mounted at the top of the base 11 for controlling the traverse or longitudinal movement of the wheelhead table 19 and the wheelhead. A suitable feed mechanism 27 is associated with the workhead table 18, as will be described more fully hereinafter, and its purpose is to feed the workpiece mounted in the workhead 21 transversely; i.e., from rear to front of the base 11.

FIGS. 3 and 4 show the manner in which the workhead table 18 and the workhead 21 are mounted on the base 11 for a feeding operation. A lower element 31 is bolted to the base 11 and, for purposes of discussion, will be considered as part of the base. Extending upwardly from the lower element 31 are rails 32 and 33, while the table 18 is provided with a way element which cooperates with the rails 32 and 33 to form hydrostatic ways in the manner shown and described in the patent of Uhlenwoldt U.S. Pat. No. 3,512,848 dated May 19, 1970. This is a self-balancing hydrostatic bearing which assures that, when the forces on the workhead table 18 (either in the horizontal or vertical direction) increase and decrease, the thickness of the oil film between the bearing surfaces does not change, so that movement does not take place in the direction of the force.

Slidable transversely relative to the lower element 31 is a block 35 having a forwardly directed shaft 36 which is slidably mounted in a ball bearing 37 mounted in a suitable flange of the lower element 31. The rear of the block 35 is provided with two flanges 38 and 39 carrying ball bearings 41 and 42, respectively. In the bearing 41 is carried a shaft 43, while a similar shaft 44 is mounted in the bearing 42, both of these shafts being mounted on suitable flanges connected to the lower element 31. The block 35 is formed with an upwardly directed recess 45 having facing vertical surfaces 46 and 47. Extending from the surface 46 is a contact member 48 which has a threaded adjustment shaft 36. This threaded adjustment takes place by means of a knob 49 which is accessible from the front of the machine. The surface 47 is provided with a fixed contact member 51. Mounted in the rear of the block 35 is a nut 52 which is engaged with a screw 53, the two elements making

up a ball-type screw-and-nut arrangement of the well-known type. The screw is mounted in a roller bearing 54 and carries at its outer end a gear 55, operably engaged by a worm 56, which in turn, is rotated by a stepping motor 57 (see FIG. 4).

Extending downwardly from the table 18 and, more specifically, from the way element 34, is a finger 58 having a plate 59 adapted to make contact with the contact member 48 and provided with an electrical sensing element 61. On the opposite side of the finger 58 (facing the contact 47) is a contact plate 62 in which is embedded an electrical sensing element 63. The sensing element 61 and 63 indicate very accurately the point of engagement of their respective contact plates with their adjacent contact members and relay this fact to the control circuits.

As is evident in FIG. 4, the wheelhead table 19 is provided with a hydraulic cylinder 60 to produce longitudinal motion, and with an oscillator 50 to provide longitudinal oscillation of the wheel 24 in the workpiece during grinding. A dressing apparatus 30 is mounted on workhead table 18.

FIGS. 5-19 show the controls for the stepping motor 57 (see FIG. 19), these controls normally being housed in the control cabinet 16. The inputs to the circuitry generally originate in various switches and gages on the machine in the well-known way and these signals are converted to pulses directed to the stepping motor 57 to cause the workhead table 18 to move forwardly and rearwardly various distances on the ways 32 and 33. The workpiece is thus caused to move transversely relative to the abrasive wheel 24 to produce a grinding cycle, including a dressing operation on the dresser 30. In the description and drawings, when a control line is labelled with the symbol /, this means that a logic "zero" produces or indicates the function, depending, of course, on the purpose for which the line signal is used.

Referring first to FIG. 5, it can be seen that signals enter the system through a NEW WHEEL COMPENSATION line 64, a FIRST SIZE RETRACTION line 65, and a SECOND SIZE RETRACTION line 66. Included in the circuit is a STANDARD COMPENSATION switch 67, a NEW WHEEL COMPENSATION switch 68, a FIRST SIZE RETRACTION switch 69, and a SECOND SIZE RETRACTION switch 71. The switches 67, 68, 69, and 71 have output lines feeding into a cable 72. Extending downwardly into the circuitry of FIG. 6 is a COMPENSATION SET PULSE / line 73. Also, extending downwardly into the circuitry of FIG. 6 is a FIRST SIZE RETRACTION PULSE / line 74, as well as a SECOND SIZE RETRACTION PULSE / line 75. A FIRST SIZE RETRACTION SET PULSE / line 76 extends from the switch 69 into the circuitry of FIG. 6, while a SECOND SIZE RETRACTION SET PULSE / line 77 extends from the switch 71 into the circuitry of FIG. 6.

Referring now to FIG. 6, it can be seen that this circuit is largely occupied by a COUNT LOGIC board 78 to which are connected the lines 73, 76, and 77 originating in the circuitry of FIG. 5. Also, of course, entering the circuitry of FIG. 6 are the lines 74 and 75 which originate in the circuit of FIG. 5. Crossing the circuit is a connected COUNTER START line 79 which is connected, not only to the post H of the board 78, but is connected into the circuit of FIG. 7. A FEED RESET line 81 is not only connected to the post 7 of the board 78, but also extends into the circuitry shown in FIG. 10.

A line 82 extends from the post P of the board 78 into the circuit of FIG. 7. A line 83 extends from the post 13 of the board 78 into the circuit of FIG. 7. A line 84 extends from the post N of the board 78 into the circuitry of FIG. 7. Line 85 extends from the post 4 of the board 78 into the circuitry of FIG. 7. A line 86 extends from the post R of the board 78 into the circuitry of FIG. 7. A line 87 extends from the post 12 of the board 78 into the circuitry of FIG. 7. A line 88 is shown as passing entirely through the circuitry of FIG. 6 from FIG. 7 to the circuitry of FIG. 9. The PICK FEED MODE element 89 is connected to a line 91 which extends into the circuitry of FIG. 7.

Continuing with a description of FIG. 6, the binding post E of the board 78 is connected by a line 92 into the circuitry of FIG. 9. The binding post 5 of the board 78 is connected by a MASTER RESET / line 93 into the circuitry of FIG. 9 and also into the circuitry of FIG. 7. The post 18 of the board 78 is connected by a DOWN / line 94 into the circuitry of FIG. 10 and also into the circuitry of FIG. 7. The post F of the board 78 is connected by a CLEAR / line 95 connected into the circuitry of FIG. 9 and also into the circuitry of FIG. 7. The post 21 of the board 78 is connected by a ZERO line 96 into the circuitry of FIG. 9. The post J of the board 78 is connected by a FEED / line 97 into the circuitry of FIG. 10. The post C of the board 78 is connected by a RETRACT / line 98 into the circuitry of FIG. 10. The post B of the board 78 is connected by a SET PULSE / line 99 and is connected into the circuitry of FIG. 9 and also into the circuitry of FIG. 7. The post D is connected by a line 101 into the circuitry of FIG. 7.

A line 102 passes through the circuitry of FIG. 6 on its way to the circuitry of FIG. 7. A FIRST SIZE / line 103 passes through FIG. 6 on its way from the circuitry of FIG. 10 to the circuitry of FIG. 7. Similarly, a line 104 passes through FIG. 6 on its way from the circuitry of FIG. 10 to the circuitry of FIG. 7. The line 105 extends from the post 6 of the board 78 into the circuitry of FIG. 7. A FEED COUNTER ZERO / line 106 extends from the circuitry of FIG. 10 through FIG. 6 into the circuitry of FIG. 7. Similarly, a SECOND SIZE / line 107 extends through FIG. 6 on its way from the circuitry of FIG. 10 to the circuitry of FIG. 7. A FEED COUNTER ZERO line 108 passes through FIG. 6 on its way from the circuitry of FIG. 10 to the circuitry of FIG. 7.

Referring now to FIG. 7, it can be seen that this particular circuit has a large number of input lines, including a FINAL SIZE RETRACTION (FEED DIRECTION) line 109, a +24 VOLT DC line 111, a STANDARD COMPENSATION (RESET DIRECTION) line 112, a STANDARD COMPENSATION (FEED DIRECTION) line 113, a CROSS SLIDE line 114, an ENERGIZE STEPPING MOTOR line 115, a SETUP MODE line 116, a FEED RESET line 117, a SECOND SIZE OVERRIDE line 118, a FIRST SIZE OVERRIDE line 119. Note that the circuitry shown in FIG. 7 includes eight input elements 121, 122, 123, 124, 125, 126, 127, and 128. The FINAL SIZE RETRACTION line 109 is connected to the input side of the input element 121, the lines 111 and 112 are connected to the input element 122. The line 113 is connected to the input 123. The lines 114 and 115 are connected to the input element 124. The FIRST SIZE OVERRIDE line 119 is connected to the input element 125. The SETUP

MODE line 116 is connected to the input element 126, the FEED RESET line 117 is connected to the input element 127, the SECOND SIZE OVERRIDE line 118 is connected to the input element 128. The circuitry of FIG. 7 also includes a FEED LOGIC board 129. The input element 121 is connected to the line 84. The input element 122 is connected to the line 82. The input element 123 is connected to the line 83. The input element 124 is connected by a line 131 to the circuitry shown in FIG. 6. The input element 125 is connected by a line 132 to the post J on the board 129. The input element 126 is connected by a line 133 to the post 18 on the board 129 and also to the line 85. The input element 127 is connected by a line 134 to the post B of the board 129 and also to a FEED RESET START / line 135 leading to the circuitry shown in FIG. 11. The input element 128 is connected by a line 136 to the post F of the logic board 129.

The post D on the logic board 129 is connected by a line 137 to the circuitry shown in FIG. 6. The post 3 of the board 129 is connected by the line 79 to the post H of the COUNT LOGIC board 78 in FIG. 6. The post H of the board 129 is connected to the line 84. The post K of the board 129 is connected to the FIRST SIZE / line 103. The post L of the board 129 is connected to the line 86. The post U of the board 129 is connected to the line 91. The post 16 of the board 129 is connected to the line 87. The post C of the board 129 is connected by a line 138 to the circuitry shown in FIG. 11. The post 21 of the board 129 is connected by a MASTER RESET line 139 to the circuitry shown in FIG. 8. The posts E, A, 2, 10, and T of the board 129 are connected, respectively, to the lines 107, 106, 102, 94, and 108. The post I of the board 129 is connected by a CLOCK 7 / line 141 to the circuitry shown in FIG. 11. Post P of the board 129 is connected to the line 104. The post Y of the board 129 is connected by a CLOCK 4 line 142 to the circuitry shown in FIG. 11. The post X of the board 129 is connected by a RETRACTION COUNT COMPLETE line 143 to the circuitry shown in FIG. 11. The post 17 of the board 129 is connected to the line 95. The post 5 of the board 129 is connected by a FEED STARTED / line 144 leading to the circuitry of FIG. 11. The post 20 of the board 129 is connected to the line 93. The post 9 of the board 129 is connected by a CARRY line 145 leading to the circuitry of FIG. 11. The post 4 of the board 129 is connected by a line 146 leading to the circuitry shown in FIG. 12. The post 8 of the board 129 is connected by a line 147 which leads to the circuitry shown in FIG. 11. The post 6 of the board 129 is connected by a line 148 which leads to the circuitry shown in FIG. 12. An ACCELERATE / line 149 passes through FIG. 7 on its way from the circuitry of FIG. 11 to the circuitry of FIG. 8. A HIGH SPEED / line 151 passes through FIG. 7 on its way from the circuitry of FIG. 11 to the circuitry of FIG. 8.

Referring now to FIG. 8, it can be seen that a major element consists of the HIGH SPEED PULSER BOARD 152 which consists of a HIGH SPEED clock 153, a FEED-RATE clock 154, and a MASTER RESET timer 155. A number of signal lines enter the circuit of FIG. 8 including a DIVIDE BY 2 OFF line 156, a RATE NO. 1 line 157, a RATE NO. 2 line 158, and a RAPID RATE line 159. Note that the clear output line 131 passes through FIG. 8 on its way from the circuitry of FIG. 7 to the circuitry of FIG. 12.

The circuit of FIG. 8 is provided with three input elements 161, 162, and 163, all of which are connected to the line 156. The output of the input element 161 is connected to the line 88; the output of the input element 162 is connected by a line 164 to the post C on the HIGH SPEED clock 153 of the PULSER board 152; and the output of the input element 163 is connected by a line 165 to the post X on the FEED RATE clock 154 of the PULSER board 152. The post B of the HIGH SPEED clock 153 is connected to the line 149, while the post Y is connected to the line 151. The post B of the HIGH SPEED clock 153 is connected by a HIGH SPEED CLOCK RATE ADJUSTMENT line 166 to the circuitry shown in FIG. 12. The post H of the HIGH SPEED clock 153 is connected by a CLOCK 1 line 167 to the circuit shown in FIG. 12. The post 4 of the FEED RATE clock 154 is connected by a CLOCK 2 INHIBIT line 168 to the circuit shown in FIG. 12. The post J of the FEED RATE clock 154 is connected by a CLOCK 2 line 169 to the circuitry shown in FIG. 12. The post R of the MASTER RESET timer 155 is connected to the line 139 leading to the circuitry of FIG. 7, while the post S is connected to a +12 VOLT source.

Referring now to FIG. 9, it can be seen that the major elements of this circuit consists of the DOWN COUNTER DIVIDER board 171 and the DECADE DOWN COUNTER boards 172. The post A of the board 171 is connected to the cable 72. The post B is connected by a line 173 to the board 172. The post C is connected to the SET PULSE / line 99. The post D is connected to the line 102. The post E is connected to the CLEAR / line 95 and the post F is connected to the DIVIDE BY 2 OFF / line 88. The posts A and B of the board 172 are connected by a jumper. The post C is connected to the line 173. The post D is connected to the CLEAR / line 95. The post E is connected to the line 102. The post F is connected to the SET PULSE / line 99. The post G is connected to the ZERO / line 92 and the post H is connected to the ZERO line 96. At the upper end of the board 172 is also connected to the cable 72, as is evident in the drawing.

The circuitry shown in FIG. 10 consists of logic elements 174, 175, 176, and 177. The input of the element 174 is connected to the line 104 and its output is connected through a line 178 to the input of the unit 175. The input of the element 175 is also connected to a line 179 which leads to the circuitry shown in FIG. 11. The output of the element 175 is connected to a FEED RESET STARTED / line 181 which leads into the circuitry shown in FIG. 14, as well as to the input side of the element 176. The input side of the element 176 is also connected to the FEED RESET / line 81, while its output is connected to the FEED RESET STARTED / line 181. The input side of the element 177 is connected to a BUFFER EMPTY / line 182 leading to the circuitry shown in FIG. 11. The input of the element 177 is also connected to the line 181, while its output is also connected to the FEED RESET / line 81. A line 183 passes through FIG. 10 on its way from the circuitry shown in FIG. 11 to the circuitry shown in FIG. 13. The line 184 passes through FIG. 10 on its way from the circuitry of FIG. 11 to the circuitry of FIG. 13. The line 185 passes through FIG. 10 on its way from the circuitry of FIG. 11 to the circuitry of FIG. 14. A RETRACT / line 186 passes through FIG. 10 on its way from the circuitry shown in FIG. 14 to another part of the circuitry shown in FIG. 14. CLOCK 8 / line 187

passes through FIG. 10 on its way from the circuitry of FIG. 14 to the circuitry of FIG. 13. Note that the line 88 also passes through FIG. 10 on its way from the circuitry shown in FIG. 13 to the circuitry shown in FIG. 14. The DOWN / line 94 passes through FIG. 10 on its way from the circuitry of FIG. 6 to the circuitry of FIG. 14.

FIG. 11 contains logic elements 188, 189, 191, 192, 193, and 194. Passing through the circuitry of FIG. 11 is the CLOCK 7 / line 141 which connects into line 185 passing into the circuitry of FIG. 10. RETRACTION COUNT COMPLETE line 143 connects to line 184 passing into the circuitry of FIG. 10. The line 182 connects to the inputs of the elements 193 and 194 and also passes into the circuitry of FIG. 15. Line 183 is connected to the input of the element 189. Line 144 connects to the inputs of the elements 188 and 191. The line 179 also connects to the input of the element 191 and is connected, on the one hand, to the input of the element 193 and, on the other hand, to the output of the element 194. The RAPID FEED COMPLETE / line 195 enters the circuit from the circuitry of FIG. 15 and is connected to the output of the element 193, as well as the input of the element 194. The FEED / line 105 is connected to the output of the element 192 and also is connected into the circuitry of FIG. 16. The line 147 passes through FIG. 11 on its way from the circuitry of FIG. 7 to the circuitry of FIG. 15. The CLOCK 4 line 142 passes through the FIG. 11 on its way from the circuitry of FIG. 7 to the circuitry of FIG. 16. The ACCELERATE / line 149 passes through FIG. 11 on its way from the circuitry of FIG. 7 to the circuitry of FIG. 16. This is also true of the line 145, 138, HIGH SPEED / line 151, and line 135. The FEED RESET / line 181 passes through FIG. 11 on its way from the circuitry of FIG. 10 to the circuitry of FIG. 16.

The CLOCK START line 101 passes through FIG. 11 on its way from the circuitry of FIG. 7 and the circuitry of FIG. 12 to the circuitry of FIG. 16. Note that the FEED STARTED / line 144 is connected to the input of both the elements 188 and 191. The SET PULSE / line 99 passes through FIG. 11 on its way from the circuitry of FIG. 7 to the circuitry of FIGS. 14 and 12. The RAPID FEED START / line 196 leaves the output of the element 189 passes to the input side of the element 193, as well as passing into the circuitry of FIG. 15. The line 197 passes from the output of the element 193 into the circuitry of FIG. 15, as well as being connected to the line 195 and also to the input of the element 194.

Referring now to FIG. 12, it can be seen that circuitry shown in that figure is provided with two input elements 198 and 199, as well as several logic elements 201 through 210. Signals are received into the circuit through AUXILIARY OUTPUT CONTACT lines 211 and 212 which are closed during the compensation and retraction portions of the cycle. POSITION RATE potentiometer 213 is connected on one side to a +12 VOLT source and on the other side to the HIGH SPEED CLOCK RATE ADJUSTMENT line 166. The CLOCK 1 line 167 is connected to the inputs of the logic elements 206, 207, and 208. The line 101 is connected to the input of the logic elements 205, 209, and 207. The CLEAR OUTPUTS line 131 passes through FIG. 12 on its way from the circuitry of FIG. 8 to the circuitry of FIG. 16. The FEED RATE / line 148 is connected to the input of the logic element 201. The clock 2 line 169 passes through FIG. 12 on its way from the

circuitry of FIG. 8 to the circuitry of FIG. 16. The CLOCK 2 INHIBIT line 168 is connected to the output of the logic element 205. Also entering the circuit is the GAP ELIMINATOR line 214 and the POSITION RATE line 215. A line 216 is connected to the input of the logic element 204 and passes into the circuitry of FIG. 16. The line 217 connects the output of the logic element 209 to the input of the logic element 210 and is also connected into the circuitry of FIG. 16. A line 218 connects the output of the logic element 210 to the input of the logic element 209 and is also connected into the circuitry of FIG. 16. The line 219 connects the output of the logic element 209 to the circuitry of FIG. 16.

FIG. 13 has as its major elements an input element 221 connected to a memory reset line 222, its output being connected to a MEMORY RESET line 223. Also located in the circuitry is a MANAGEMENT CONTROL board 224 connected to the input cable 72, while leading from it is a BCD OUTPUT cable 225. Included in the circuitry is a DUAL DECODER board 226, and a DUAL DECODER board 227. These decoder boards are connected to a 7 SEGMENT READ-OUT buss 228 and to a cable 229. Finally the circuit board provided with an INPUT register 231 connected to the cable 225 and also to the cable 229, as well as a THREE DECADE COMPARATOR board 232 connected to the cable 229, which cable passes not only to the circuitry of FIG. 17, but also to the circuitry of FIG. 14. The post Y of the register 231 is connected to the MASTER RESET / line 93. The post X of the register 231 is connected to the MEMORY RESET / line 223. The post V is connected to the line 98. The post U is connected to the line 184. The post 20 of the COMPARATOR board 232 is connected to the line 183. The post end of the COMPARATOR board is connected to the CLOCK 8 / line 187. Line 88 passes through FIG. 13 on its way from the circuitry of FIG. 9 to the circuitry of FIG. 10.

Referring now to FIG. 14, it can be seen that this circuit is provided with a FEED COUNTER DIVIDER board 233 and with THREE DECADE FEED COUNTER boards 234. Also included in the circuitry of FIG. 14 are logic elements 235 through 239. The DOWN / line 94 is connected to the post H of the board 233 and to the post A of the board 234. The RETRACT / line 186 is connected to the input of the logic element 235. The line 108 passes through FIG. 14 on its way from the circuitry of FIG. 10 to the circuitry of FIG. 18. This is true also of the line 107. The line 88 is connected to the post F of the board 233 and also passes into the circuitry of FIG. 15. The FEED COUNTER ZERO / line 106 passes through FIG. 14 on its way from the circuitry of FIG. 10 to the circuitry of FIG. 18. The line 185 is connected to the input of the logic element 236. The line 181 is connected to the input of the logic element 237. The line 195 is connected to the input of the logic element 237, while the line 181 also passes into the circuitry of FIG. 15. The line 196 also is connected to the input of the logic element 237. The line 187 is connected to the output of the logic element 239 and also to the post E of the board 234, as well as passing into the circuitry of FIG. 18. The line 93 connected to the post D of the board 233 and also passes into the circuitry of FIG. 15, as well as being connected to the post F of the board 234. The ZERO line 230 leaves the post G of the board 234 and

enters the circuitry of FIG. 18. The CARRY line 237 leaves the post H of the board 234 and enters the circuitry of FIG. 15.

In the circuit of FIG. 15 is included a DECELERATION BUFFER board 238 associated with input elements 239 and 241 and with logic elements 242 through 247. Also entering the circuit is the RETRACT LIMIT line 249 which is connected to the input side of the input element 239 and a FEED LIMIT line 250 which is connected to the input side of the input element 241. The line 181 is connected to the post B of the BUFFER board 238. The line 187 simply passes through FIG. 15 on its way from the circuitry of FIG. 10 to the circuitry of FIG. 14. The line 186 passes through FIG. 15 on its way from the circuitry of FIG. 10 to the circuitry of FIG. 16. The line 103 passes through FIG. 15 of its way from the circuitry of FIG. 10 to the circuitry of FIG. 18. The line 98 passes through FIG. 15 on its way from the circuitry of FIG. 10 to the circuitry of FIG. 16. This is true also of line 97. Line 99 is connected to the input side of the logic element 246. Line 195, of course, passes through FIG. 15 on its way from the circuitry of FIG. 11 to the circuitry of FIG. 14. Line 196 is connected to the input of the logic circuit 245. Line 183 is connected not only to the input of the logic element 247, but is also connected as a BUFFER EMPTY line to post E of the board 238. Line 197 is connected to the input of the logic element 243, while the line 147 is connected to its output. The output of the logic element 246 is connected to the line 149. Line 237 passes through the FIG. 15 on the way from the circuitry of FIG. 14 to the circuitry of FIG. 16. The output of the logic element 244 is connected to a line 245, HIGH SPEED / line 248, which is connected first of all to the input of the logic unit 246, also passes downwardly into the circuitry shown in FIG. 16 (where it is connected to the line 151) and also is connected to the A post of the board 238. Note that line 101 is connected into the circuitry of FIG. 16 and also is connected at the other end to a CLOCK START terminal. The line 251 is connected from the output of the input element 241 to the circuit of FIG. 16. The RETRACT LIMIT / line 252 is connected from the output of the input element 239 to the circuit of FIG. 16. Line 88 passes through FIG. 15 as it goes from the circuitry of FIG. 14 to the circuitry of FIG. 16. Line 93 also is connected to the D post of the board 238, while it also passes downwardly into the circuitry of FIG. 16. The CLOCK 5 / line 253 is connected to the G post of the board 238 and extends downwardly into the circuitry of FIG. 16. A BUFFER EMPTY / line 250 is connected to the post E of the board 238. A BUFFER EMPTY line 254 is connected to the post E, extends in one direction into the circuitry of FIG. 19, and extends in the other direction down into the circuitry of FIG. 16.

Referring now to FIG. 16, the circuitry includes as its major element a PULSE-TO-STEP CONVERTER board 255, as well as a ONE-SHOT multivibrator 256. The circuit also includes input elements 257 and 258. The input side of the input element 257 is connected to a FEED STOP line 259, while the input side of the input element 257 is connected to a FEED START line 261. Also located around the circuitry are a number of logic elements 262 through 274. The CLOCK 4 line 142 is connected to a line 275 which joins one side of the multivibrator 256 to the input sides of the logic units 273 and 274. The line 101 simply passes through

FIG. 16. The line 149 also passes through the FIG. 16, while line 145 also passes through the FIG. 16. The line 138 is a FEED MODE / line and connects to the output of the logic unit 271, as well as the input of the logic unit 272. Line 151 joins line 248 passing through the circuitry of FIG. 15 and also connects to the input side of the logic unit 273. The line 105 is connected to the post P of the convertor board 255. The line 135 is a FEED RESET START / line which is connected to the input of the logic unit 267. The FEED RESET / line 181 is connected to the post W on the board 255. The CLOCK START line 101 is connected to the input side of the logic element 273. The line 216 is connected to the output of the logic unit 262 and to the input of the logic unit 264. The line 169 is connected to the input of the logic unit 262. The line 217 is also connected to the input of the logic element 262. The line 218 is connected to the input side of the logic element 263 as is the line 219. The input sides of the logic element 262 and 263 are also connected by a line 276 to the post 19 of the board 255. The CLEAR OUTPUTS line 131 is connected to the input side of the logic element 265. A 270° INPUT line 277 is connected on the one end to the post D of the board 255 and extends out of the circuit into the circuitry of FIG. 19. In a similar way a 90° INPUT line 278 extends from the post C of the board 255 into the circuitry of FIG. 19. A 180° INPUT line 279 extends from the post B of the board 255 into the circuitry of FIG. 19. A 0° INPUT line 281 extends from the post A of the board 255 into the circuitry of FIG. 19.

Continuing with the description of the circuitry shown in FIG. 16, MASTER RESET / line 93 enters the circuitry from the circuitry of FIG. 15 and is connected to the input side of the logic element 271. Similarly the BUFFER EMPTY line 254 is connected to the input side of the logic element 270. The CLOCK 5 / line 253 is connected to the logic unit 274 and also is connected to the input of the logic element 269. The MASTER RESET / line 93 is connected to the post E of the board 255, the line 88 is connected to the post F of the board 255, the line 186 is connected to the post 13 of the board 255, the line 252 is connected to the post 20 of the board 255, and line 251 is connected to post 21. The FEED / line 97 is connected to the post N and the board 255. It will be recalled that the line 248 is connected not only to the line 151, but it is also connected to the input side of the logic element 273. The line 98 is a RETRACT / line and it is connected to the post V of the converter board 255.

Referring now to FIG. 17, it can be seen that the 7 SEGMENT READOUT BUSS cable 228 is connected to a 3-DIGIT readout 282. The cable 229 is connected to a SECOND SIZE switch 283 to an INTERMEDIATE SIZE switch 284 and to a FIRST SIZE switch 285, these switches being the thumb-wheel digital type of switch known as a "DIGISWITCH." The circuit shown in FIG. 17 includes a number of logic elements 286 through 294 leading to various output lines which are connected elsewhere in the circuitry. For instance, there are three SECOND SIZE output lines 287, 288, and 289. There are three INTERMEDIATE SIZE output lines 291, 292, and 293. There are three FIRST SIZE output lines 294, 295, and 296. These lines contain normally open and normally closed contactors operated by relays 1RR, 2RR, and 3RR, as is shown in the drawing. Various parts of the circuit of FIG. 17 are

connected to the circuitry of FIG. 18. For instance, a line 297 is connected to the input of the logic element 288 and extends to the circuitry of FIG. 18. The line 298 is connected to the input of logic element 293 and to the relay 1RR, and also is connected back into the circuitry of FIG. 18. A line 299 is connected to all of the input of the logic elements 290, 292, and 294 and is also connected into the circuitry of FIG. 18. A line 301 connected to the input of the logic element 287 and it is also connected down into the circuitry of FIG. 18. The line 302 is connected to a line joining the input of the logic element 289 to the relay 3RR and is also connected down into the circuitry of FIG. 18. A line 303 is connected to the input side of the logic element 286 and extends downwardly into the circuitry of FIG. 18.

Referring now to FIG. 18, it can be seen that the circuitry includes logic elements 304 through 308 associated with a relay 4RR. The contactors associated with the relay are connected to FEED RESET OUTPUT lines 309, 311, and 312. The FEED COUNTER ZERO / line 106 is connected to the line 299 passing to the circuitry shown in FIG. 17 and it is also connected to a line joining the input and output of the logic elements 306 and 304, respectively. The ZERO line 230 is connected to the input of the logic element 304. The SECOND SIZE / line 107 only passes through FIG. 18 from the circuitry of FIG. 14 on its way to the circuitry of FIG. 17. The FEED COUNTER ZERO line 108 is connected to the output of the logic element 306 and also to the input of the logic element 305. The BUFFER EMPTY line 254 is connected to the input of the logic element 305. The CLOCK 8 / line 187 is connected to the line 297 and also to the line 303 and to the input of the logic element 304. The FIRST SIZE / line 103 is connected to the line 298 passing into the circuitry of FIG. 17.

FIG. 19 shows the circuitry associated with the stepping motor 57 and includes a POWER MOTOR DRIVER board 313, a POWER SUPPLY switch 314, a transformer 315, and a rectifier bridge 316. The transformer is connected to the input lines 317 and 318, connected to 125-volt source. A thyrector 319 is connected across the secondary of the transformer. The output of the rectifier is connected to the posts A, B, C, and D of the POWER SUPPLY switch 314. Also, posts F, H, J, and K of that switch are connected by a line 321 to a +24 DC source. Output posts M, N, P, and R of the switch 314 are connected by a line 322 to the posts 2 and 6 of the stepping motor 57. The same posts M, N, P, and R of the switch 314 are connected to the suppressor posts P and X of the POWER MOTOR DRIVER board 313 by a line 323. The 0° INPUT line 281 is connected to the post K of the board 313. The 180° INPUT line 279 is connected to the post B, the 90° INPUT line 278 is connected to the post R, and the 270° INPUT line 277 is connected to the post L of the board 313. A line 324 connects the post E and D of the board 313 to the post 1 of the stepping motor 57, the post M and N are connected by a line 325 to the post 3 of the motor, the post V and W of the board 313 are connected by a line 326 to the post 4 of the motor 57, and the post T and U of the board 313 are connected by a line 327 to the post 5 of the motor.

The operation of the apparatus will now be readily understood in view of the above description. First of all, the machine features the use of high speed stepping

of the feed motor, of half stepping, and of high-voltage switching on the motor windings. The addition of a half-step mode of operation (which makes the stepping motor move in 0.9° increments, instead of 1.8° increments) requires a special 8-step sequence of the motor windings instead of the 4-step sequence used on standard units. Using this half-step mode, the motor can be stepped twice as fast as with full stepping, since the shaft speed of the motor is the same in both cases. The advantage is that a gear train of 20 to 1 instead of 40 to 1 can be used on the lead screw. This doubles the speed of the slide but still gives the same resolution as the 40-to-1 gears formerly used with full stepping.

The use of the half-step mode also has the advantage of minimizing the effect of motor resonance on output torque. This is because in the half-step mode of operation it alternates between one and two windings energized at once. The natural frequency is different for two windings energized than for one winding energized. Either of these natural frequencies will resonant enough so that the resonance will cause the motor to lose sufficient torque and drop out of synchronization with the pulse train when the motor is stepped at these speeds. The driver of board 313 (which is used to sequence the motor 57) is designed in a manner such that the motor can be operated in either mode. To change from half-step to full-step mode of operation requires only the addition of a jumper line which is external to the board.

High-speed stepping was incorporated in the apparatus for positioning the workhead cross slide relative to the abrasive wheel. The design used a voltage-controlled oscillator or a pulsing circuit with a frequency range from 800 to 6,000 Hertz. This is incorporated in the HIGH SPEED clock 153. This rate is controlled by means of an adjustable R-C network that is used for accelerating and decelerating the stepping motor 57 in the half-step mode. If the full-step mode is used, the pulsing ranges change to a 400 to 3,000 Hertz range by means of an external jumper. The HIGH SPEED PULSER board 152 is designed with an overide circuit that switches the pulser to its maximum instantaneously, thus, bypassing the R-C network. This feature is used to supply pulses to the FEED COUNTER board 234 and the DECELERATION BUFFER board 238 before the stepping motor 57 is gated to the pulse train. The sequence of operation of this high speed system is as follows:

Assuming that the cross slide (workhead slide 18) is feeding at a certain grinding rate with the amount of feed from the feed counter 234 displayed on the digital feed readout 282, the signal from the machine control next calls for a "dress interrupt" which requires that the feed be reset to zero, i.e., the table moved rearwardly to bring the dressing apparatus 30 in line with the abrasive wheel 24. When this FEED RESET signal is received, the feed system switches from the FEED mode to the FEED RESET mode. This loads a retraction count in the DOWN COUNTER board 172 and turns the pulser 152 on at high speed, using the overide circuit. The pulses are gated into the "down" terminal of the FEED COUNTER board 234, to the "add" terminal of the DECELERATION BUFFER board 238 and the DOWN COUNTER board 172. When the DOWN COUNTER board 172 reaches zero, it gates the A register "off" on the COMPARATOR board. This holds the count that was on the FEED COUNTER

board 234 at the time the down counter reached zero to be used as a reference position later. This count represents the last feed position less a fixed retraction. The DECELERATION BUFFER board 238 will next give a signal that it has counted a pre-programmed number of pulses (say, 300) called a "buffer-filled signal." This signal will instantly switch the pulsing rate to 800 Hertz, will gate the deceleration buffer out, and will gate pulses to the retract input of the PULSE-TO-STEP convertor board 255. This board 255 controls the stepping motor direction and speed. At the same time, an acceleration signal is gated to the high-speed pulser, causing it to change from 800 to 6,000 Hertz at a rate determined by the R-C network. The next signal that should be received is a FEED COUNTER ZERO signal. This signal gates out the FEED COUNTER board 234 and gates pulses to the "subtract" input of the DECELERATION BUFFER board 255. The high-speed pulser also receives a deceleration signal at this time, which causes the pulses to go back to the 800 Hertz condition at a rate which again is determined by the R-C network. This R-C network is adjusted such that the BUFFER EMPTY signal is received at approximately the same time that the pulse rate has dropped back to the 800 Hertz rate. When the BUFFER EMPTY signal is received, the cycle has been completed and the pulser is gated "off." In some instances, there may be less feed to reset than it takes to fill the deceleration buffer. If this is the case, the counter will reach zero before the buffer gets filled. This will gate the PULSE-TO-STEP convertor "on" and empty the buffer at the 800 Hertz rate and it will not accelerate in this case.

In the case where the abrasive wheel is to be indexed back to the workpiece after the dressing operation has been completed, a cycle very similar to the feed reset cycle takes place. A FEED START signal will turn the pulser "on" at the high rate, using the overide input on the high-speed pulser. The pulses are gated to the "add" input of the DECELERATION BUFFER board 255 and to the "up" input of the FEED COUNTER board 238. As soon as the buffer-filled signal is obtained (300 pulses), the buffer is gated out and the PULSE-TO-STEP convertor is gated "in" at the 800 Hertz gate. The acceleration input is also energized at this point, causing the pulser to change to the 6,000 Hertz rate at a rate of acceleration determined by the R-C time constant. This pulse rate continues until the count-out of the FEED COUNTER board 238 is not less than the count that was stored in the A register 231 of the COMPARATOR board 232.

At this time a signal from the COMPARATOR board 232 will stop the FEED COUNTER board 238 and gate "subtraction" pulses to the DECELERATION BUFFER board 255. Also, at this time the pulser 152 is put in the deceleration mode and the pulser changes back to the 800 Hertz rate as a function of the R-C network. When the buffer-empty signal is received, the HIGH SPEED clock 153 is turned off and the FEED-RATE clock 154 is gated in. Also, the FEED COUNTER board 234 is gated back "in" and the BUFFER board 238 is gated "out." The pulse rate continues at this feed rate until a size signal (or another interrupt signal) is received.

In some instances there will be a lower count stored in the A register 231 of comparator 232 than it takes to fill the DECELERATION BUFFER board 238. If

this is the case, an output will be obtained from the COMPARATOR board before the buffer gets filled. This will gate the PULSE-TO-STEP CONVERTOR board 255 on and empty the buffer at the 800 Hertz rate and it will not accelerate in this case.

It should be noted that a power switching system was designed for this apparatus because of a reduction in torque at the higher stepping rates. This torque reduction is due to the slow build up of current in the motor windings because of their relatively high inductance. By using a large resistance in series with the motor winding, the L/R time constant is reduced. This makes the circuit appear more resistive than inductive and the current will build up much faster. In order to use this large resistance the supply voltage for that stepping motor must be increased in order to keep rated current through the motor for maximum torque. The high speed feed system is designed using 100 volts DC for the stepping motor and two 25 ohm 500 watt current limiting resistors. Because of the large amount of heat dissipated (800 watts) by these resistors an electronic switch was designed to switch the supply voltage from 24 to 100 volts DC when stepping. This reduces the heat dissipation to approximately 20 watts when the stepping motor is at rest. The motor, however, will still have enough holding torque to hold the load in position under this condition.

It can be seen that the present grinding machine permits a high speed retraction and return from a dressing operation, while retaining the advantages of stepping motor feed. Since the movement of the movable table or cross feed during the travel to "dress" position and returning forward to "grinding" position is wasted time, the use of the high-speed stepping operation will have the effect of reducing the entire cycle time for grinding a workpiece. Furthermore, the part of the cycle which is reduced is the part which is not concerned with grinding and, since grinding is the important function of the machine in the first place, this means that substantially more of the machine time will be used doing the actual grinding operation. This is in conformity with the best business practice of using a high capital cost machine for its functional operation during as much time as possible, since the cost of maintaining the machine in the machine shop in the first place, takes place continuously 24 hours a day. Furthermore, the operation of performing the high-speed pulsing is done in such a way that the stepping motor does not lose synchronization with the incoming pulses. This is important, of course, because the counting apparatus which keeps track of the number of pulses going to and from the motor is used to determine the position of the workpiece and the abrasive wheel relative to one another by the "dead reckoning" method. If one or more pulses are "lost," the counter no longer really knows where the elements of the grinding machine are relative to one another. Such a pulse would be "lost" if the pulse were transmitted to the stepping motor, but the stepping motor did not rotate through its usual increment in response to that particular pulse. While the loss of one pulse might not immediately result in a poor workpiece, the effect of lost pulses is accumulative and the counters become less and less indicative of the true situation, so that it is eventually necessary to stop the machine and correct the counter which is a time-consuming operation.

It is obvious that minor changes may be made in the form and construction of the invention without departing from the material spirit thereof. It is not, however, desired to confine the invention to the exact form herein shown and described, but it is desired to include all such as properly come within the scope claimed.

The invention having been thus described, what is claimed as new and desired to secure by Letters Patent is:

10. 1. A grinding machine, comprising
  - a. a base,
  - b. a workhead slide mounted on the base,
  - c. a wheelhead slide mounted on the base,
  - d. a feed mechanism, including a stepping motor, for producing transverse relative movement between the slides to produce a grinding cycle,
  - e. a first pulse generator having a first section for producing pulses at a first rate and a second section for producing pulses at a second rate which is substantially greater than the first rate, and
  - f. a control means for introducing pulses from the first section to the stepping motor during a portion of the grinding cycle and for introducing pulses from the second section to the stepping motor during another portion of the grinding cycle, the control means including a shifter means operative during an interval when the rate of pulses introduced to the stepping motor is changed between a first value and a second value, to introduce to the stepping motor pulses at rates of smoothly changing value thereby avoiding loss of synchronization between the stepping motor and pulses during the change.
20. 2. A grinding machine as recited in claim 1, wherein the shifter provides for changing the rate along an acceleration curve from the smaller to the larger of the two pulse rates and along a deceleration curve from the larger to the smaller.
30. 3. A grinding machine as recited in claim 2, wherein the workhead slide carries a workhead in which a workpiece is mounted for rotation about the axis of an internal surface of revolution that is to be formed on the workpiece, wherein the wheelhead slide carries a wheelhead in which is rotatably mounted a spindle having an abrasive wheel at one end, and wherein a dressing apparatus is mounted for engagement on occasion by the wheel.
40. 4. A grinding machine as recited in claim 3, wherein the control means connects the pulse generator to the stepping motor to retract the wheel from the workpiece to a base line for treatment by the dressing apparatus and returns it to the workpiece for further grinding.
50. 5. A grinding machine as recited in claim 4, wherein the retraction movement is started using the first pulse rate, rapidly and smoothly accelerating to the second pulse rate, remaining at the second pulse rate during most of the retraction, and rapidly and smoothly decelerating to the first pulse rate again at the end of the retraction, and wherein the procedure is reversed during the return movement.
60. 6. A grinding machine as recited in claim 5, wherein a counter is provided for up counting the pulses required to move the wheel from the workpiece to the dressing apparatus and for down counting the pulses to return.
65. 7. A grinding machine as recited in claim 5, wherein a buffer counter is loaded with a predetermined pulse

count to determine the point at which deceleration begins during retraction and again during return.

8. A grinding machine as recited in claim 7, wherein the control means acts to switch instantaneously from the first pulse rate to the second pulse rate to feed pulses to the deceleration buffer counter.

9. A grinding machine as recited in claim 7, wherein the control means acts to feed the second pulse rate to a down counter and to the deceleration buffer counter before feeding the second pulse rate to the stepping motor for the retraction movement.

10. A grinding machine as recited in claim 9, wherein the control means acts after the dressing operation to

feed second rate pulses to again load the deceleration buffer counter before feeding second rate pulses to the stepping motor for the return movement.

11. A grinding machine as recited in claim 1, wherein a feed counter and buffer are provided, the feed counter normally counting the pulses that are introduced to the stepping motor, and the control means being adapted to cause at least one pulse to be counted by the feed counter but stored in the buffer and to be fed to the stepping motor only after the occurrence of a latter event.
